UNITED STATES PATENT OFFICE.

CHARLES HERMAN HAESELER AND ALBERT H. TAYLOR, OF PHILADELPHIA,
PENNSYLVANIA.

ROTARY DRILL.

SPECIFICATION forming part of Letters Patent No. 721,037, dated February 17, 1903.

Application filed June 18, 1901. Renewed December 19, 1902. Serial No. 135,947. (No model.)

To all whom it may concern:

Be it known that we, CHARLES HERMAN HAESELER and ALBERT H. TAYLOR, citizens of the United States, residing at Philadelphia, 5 in the county of Philadelphia and State of Pennsylvania, have invented certain new and useful Improvements in Rotary Drills; and we do hereby declare the following to be a full, clear, and exact description of the invention, such as will enable others skilled in the art to which it appertains to make and use the same.

Our invention relates to an improvement in rotary drills; and the object of our invention is to produce a device of this character which will be light, shall comprise few parts, and will be simple and effective in operation.

With this object in view our invention consists in the construction and combinations of 20 parts, as hereinafter described and claimed.

In the accompanying drawings, Figure 1 is a vertical longitudinal section of our device. Fig. 2 is a cross-section on the line 2 2 of Fig. 1. Fig. 3 is a cross-section on the line 3 3 of 25 Fig. 1. Fig. 4 is a section on the line 4 4 of Fig. 1. Fig. 5 is an elevation, partly in section, of the valve-containing cylinder. Fig. 6 is a view of the same in a different position, and Fig. 7 is a perspective view of the valve.

30 The casing of the drill is composed of an upper part *a* and a lower part *b*, fastened thereto by screws *c d*. In the lower casing are air-ports *e f* for the escape of air or other motor fluid which is used to run the drill, or 35 the lower part of the casing may be of open-work for the same purpose. The casing *b* is provided with a cylindrical projection *g*, in which the tool-operating part is located. The upper part of the casing *a* is provided with a 40 screw-threaded projection *h* for the reception of the pipe *n*, through which air or steam is conveyed to the drill. The part *h* is also provided with a shoulder *i* for a purpose hereinafter to be described. The upper part of 45 the casing *a* is provided with a projection *k*, screw-threaded at *l*. This projection *k* is perforated for the passage of the valve-cylinder.

m represents a bolt screwed into the part *k* for the purpose of confining the cylinder 69, 50 hereinafter to be described.

o is a thimble abutting against the shoulder *i* and screwed into another thimble *p*, to which is connected the air-pipe *q*, which conveys the air to the operating-cylinders.

v represents a ring provided with a passage 55 *j*, which connects with the pipe *q*, and this ring is secured in shoulders in the enlargement *k* in the upper part of the casing. This ring is also perforated at one side of its center for the reception of the valve-cylinder. 6c

Around the ring *v* is a circular wear-plate *t*, L-shaped in cross-section, on which are supported antifriction-balls *u*, upon which balls rests another circular stepped wear-plate *s*. The wear-plate *s* is secured in the ring *r*. 65

w represents a spider-arm (there preferably being three of these) attached to or made integral with the ring *r* and provided with a downwardly-projecting thimble *x* at its outer end. This thimble *x* is perforated for the reception of a hollow sleeve *y*, which is surrounded by a hardened wear-sleeve *z*, which sleeve is in turn surrounded by an extended sleeve *73*, carried on the piston-rod *40*. The sleeve *y* is secured in position by the bolt *2*, 75 which passes through the extension *1* of the crank-arm *3*. This crank-arm terminates in a head *5*, perforated and screw-threaded, and in this head *5* by means of the screw *4* is fastened the gear-wheel *6*, which is arranged 80 centrally of the drill immediately under the handle and immediately over the tool. This central gear-wheel *6* meshes with gear-wheels *7* and *8*, (see Fig. 1;) but preferably three of these gear-wheels are used. These gear-wheels are mounted upon pins *9* and *10*, having reduced lower portions *11* and *12*, the upper part of the pins being surrounded by hardened wear-sleeves *13* and *14*. These gear-wheels mesh with a stationary circular 85 rack *74*, having internal teeth, as shown in Fig. 3.

The lower part 15 of the shaft carrying the gear-wheel *6* is surrounded by a hardened wear-sleeve *16*, and both of these are supported in a perforation in a spider-frame *17*, in which the lower parts *11* and *12* of the pins *9* and *10* are mounted. This spider-frame has a cylindrical extension *18*, the lower part of which is shouldered, as shown at *19*, and 90 *100*

provided with a double-threaded extension 20, with which the circular nuts 21 and 22 engage.

23 and 24 represent circular hardened wear-
5 plates, the two together providing a channel for the reception of the antifriction-balls 25.

26 represents the tool-holder, bored out at
10 27 for the reception of a drill or other tool and provided with an opening 28 for the reception
15 of a cotter or pin. This tool-holder is confined in the cylinder 18 by means of the nut 21 and the pin 29. The valve-cylinder is best shown in Figs. 5 and 6. It is provided with an enlarged portion 30, which has a holder-
bore 58 and a screw-threaded lower opening

55, an inlet-port 75, an exhaust-port 76, a perforation 56 for the reception of a securing-pin, a shoulder 57, a smaller internal bore 59, ports 60 for the admission of air, and a plate
20 63, preferably of hardened metal, on which is supported a gear-wheel 61, fastened to the top of the valve-cylinder by the screw 62. The valve is shown in perspective in Fig. 7. It consists of a rectangular plate 50, provided
25 with a concave upper portion 51, a circular portion 52, and a flat portion 53. A hole 54 is made in the circular portion 52 for the reception of a securing-pin which passes through the hole 56 in the valve casing or cylinder.

30 We preferably use three cylinders 34, 35, and 36, one hundred and twenty degrees apart. These are all cast solid around a central support 31, triangular in cross-section, which is perforated centrally for the passage of the
35 valve cylinder or casing 30. This support 31 is provided with three admission-ports 46, 47, and 48, one for each cylinder, and an equal number of exhaust-ports, one of which, 49, is shown in Fig. 1. These cylinders, with their
40 central support, are held in place on the valve cylinder or casing by a perforated washer 32, beveled, as shown in Fig. 1, which washer is secured to the valve-casing by a hollow nut 33. In the cylinders 34, 35, and 36 are pis-
45 tons 37, 38, and 39. These pistons are pivoted, by means of the pivots 43, 44, and 45, to piston rods or arms 40, 41, and 42. These piston-rods at their outer ends are pivoted to extended sleeves, one instance being shown
50 in Fig. 1, where the arm 40 is provided with a sleeve 73, which is pivoted on the sleeve y, there being an interposed wear-piece z.

55 Mounted on top of the casing is mechanism for stopping, starting, and reversing the drill. The cylinder 64 is screw-threaded upon the extension k. This cylinder is reduced to form a smaller cylinder 66 at its top, screw-threaded at 65.

60 67 represents the reversing-handle, which is secured by a pin 72 to a sleeve 68, which is provided with a hollow passage 71 for the admission of oil to the machine. The sleeve 68 is enlarged, forming a cylinder 69, which fits within the cylinder 64 and is partially
65 confined in place by the bolt m. The cylinder 69 is provided with internal gear-teeth
70, extending about half-way around the cyl-

inder. These gear-teeth mesh with the gear-wheel 61 on the valve-cylinder 30.

In the normal position, as shown in Figs. 1 70 and 4, the valve-cylinder is in such a position that there is a clear passage for the air through the pipe q to the interior of the cylinders. By moving the handle in either direction forty-five degrees the passages 60 in the valve-cylinder 75 no longer communicate with the passage in the pipe q, the supply of air to the cylinder is cut off, and the drill is stopped. If then it is turned forty-five degrees more, the motion of the drill is reversed, this action 80 being useful in withdrawing the drill from its work.

The operation is as follows: When the handle 67 is in the position shown in Fig. 1, air is admitted through the pipe n, tube q, and 85 valve-cylinder behind the two pistons 37 and 39, as shown in Fig. 3. This causes the pistons to move outwardly, rotating the gear 6, which in turn rotates the gears 7 and 8 and by means of the stationary rack 74 causes all 90 the cylinders, with their pistons and connections, including the tool-holder, to rotate. At the time when air is being admitted to the two cylinders 34 and 35 it is being exhausted from the cylinder 36 through the air-ports 95 49 and 76. Thus it will be seen that air is admitted to two of the cylinders at once, which gives great power to the machine. The operation of the machine is very rapid, the revolutions being as high as two thousand per 100 minute in some instances.

It is understood that many changes might be made without departing from the spirit of our invention, and we wish it to be expressly understood that we do not limit ourselves to 105 the exact details shown and described.

Having thus described our invention, what we claim as new, and desire to secure by Letters Patent of the United States, is—

1. In a rotary drill, the combination of a 110 central perforated support and cylinders cast integral therewith, a spider-ring, crank-arms, connections between said ring and arms, pistons in said cylinders, piston-rods pivotally connected to said connections and said pistons, and means for admitting, cutting off and changing the direction of the motor fluid admitted to said cylinders, said means including a handle for supporting the drill.

2. In a rotary drill, the combination of a series of cylinders, pistons in said cylinders, piston-rods pivotally connected to said pistons, a valve-cylinder communicating with said cylinders, a valve in said cylinder, and means for turning said valve-cylinder, where- 125 by the workman may stop, start and reverse the movement of said pistons.

3. In a rotary drill, the combination of a cas- 130 ing provided with an internal gear, crank-arms, gearing between said crank-arms and said internal gear, a spider-ring, connections between said arms and ring, a plurality of cylinders and pistons, piston-rods pivotally connected to said connections and said pis-

tons, and means for governing the entrance and discharge of the motor fluid to and from said cylinders.

4. In a rotary drill, the combination of a casing made in two parts, one of said parts being provided with a cylindrical extension and having an internal gear, crank-arms, gearing between said internal gear and said crank-arms, a spider-ring, connections between said crank-arms and spider-ring, a plurality of cylinders, pistons in said cylinders, piston-rods pivotally connected to said connections and to said pistons, and a spider-frame having a cylindrical extension.

15 5. In a rotary drill, the combination of a casing, a valve-cylinder open at one end supported on said casing, a perforated support revolubly mounted on said valve-cylinder, a plurality of operating-cylinders provided with inlet and outlet ports cast integral with said support, said support having a beveled end, a beveled washer engaging said end, and a perforated nut securing said valve-cylinder, washer and support together.

25 6. In a rotary drill, the combination of a casing, a valve-cylinder closed at one end and open at the other and provided with inlet and outlet openings mounted in said casing, a perforated central support, a plurality of cylinders each provided with inlet and outlet ports and made integral with said central support, a perforated nut and washer for securing said valve-cylinder and said support together, and a valve in said valve-cylinder having a portion entirely filling the bore of said cylinder, said portion being located between the inlet and outlet ports of the operating-cylinders.

35 7. In a rotary drill, the combination of a casing, a valve-cylinder supported in said casing, a handle supported by said casing, said handle and said valve-cylinder being provided with connecting-gear, whereby by turning the handle the flow of the motor fluid in said valve-cylinder may be regulated.

45 8. In a rotary drill, the combination of a casing having a perforated extension, a valve cylinder located in the perforation in said casing and provided with a supporting-plate resting on said extension and a gear-wheel mounted above said supporting-plate, a regulating-cylinder provided with internal gear-teeth meshing with gear-wheels on said valve-cylinder, and a handle connected to said regulating-cylinder, whereby the flow of motor fluid in said valve-cylinder may be regulated or stopped altogether.

55 9. In a rotary drill, the combination of a valve-cylinder provided with a gear-wheel, a regulating-cylinder having internal teeth meshing with the teeth of said gear-wheel and a handle connected to said regulating-cylinder, the parts being so arranged that when the gear-wheel on the valve-cylinder is located centrally in respect to the gear-teeth on the regulating-cylinder, a movement of the handle in either direction will cut off the motor fluid from said valve-cylinder, and a further

movement in the same direction will reverse the movements of the parts operated by the motor fluid.

10. In a rotary drill, the combination of a casing provided with a perforated extension, a perforated valve-cylinder having a closed upper end and a gear-wheel attached to said end located in said extension, a screw-threaded cylinder screwed upon the extension of said casing, a regulating-cylinder provided with internal gear-teeth located in said screw-threaded cylinder, and a handle attached to said regulating-cylinder.

15 11. In a rotary drill, the combination of a casing having a perforated extension, a screw-threaded cylinder composed of two cylinders of different sizes placed end to end, the larger of said cylinders being secured to the extension on the casing, a regulating-cylinder composed of two cylinders placed end to end and having gear-teeth in the larger of said cylinders, and a handle fastened to the smaller part of the regulating-cylinder.

20 12. In a rotary drill, the combination of a casing provided with an extension, a regulating-cylinder provided with internal teeth, a screw-threaded cylinder surrounding said regulating-cylinder and secured to said extension, a guiding-bolt engaging one side of said regulating-cylinder and screwed into said extension, and a handle secured to said regulating-cylinder.

25 13. In a rotary drill, the combination of a casing provided with a perforated extension, a screw-threaded cylinder engaging said extension, a regulating-cylinder provided with internal teeth secured within said screw-threaded cylinder, a bolt engaging one side of said regulating-cylinder, a handle secured to said regulating-cylinder, and a valve-cylinder having a gear-wheel engaging the teeth in said regulating-cylinder.

30 14. In a rotary drill, the combination with a casing provided with a perforated extension, a screw-threaded cylinder fastened to said extension, a regulating-cylinder provided with internal teeth within said screw-threaded cylinder, a bolt screwed into said extension and engaging one side of said regulating-cylinder, a handle secured to said regulating-cylinder, a valve-cylinder closed at one end passing through the perforation in said extension, said valve-cylinder being provided with a plate resting upon said extension, and a gear-wheel fastened to the upper end of said valve-cylinder and engaging the teeth on said regulating-cylinder.

35 15. In a rotary drill, the combination of a casing provided with a perforated extension, a securing-cylinder screwed to said extension and provided at one end with an extension forming a smaller cylinder, a regulating-cylinder provided with internal teeth and composed of two cylinders placed end to end, a handle secured to the smaller part of the regulating-cylinder which is open from top to bottom and a valve-cylinder closed at one end

- and having a gear-wheel fastened to the closed end thereof which gear-wheel engages with the internal teeth on the regulating-cylinder.
16. In a rotary drill, the combination with 5 a casing provided with a perforated extension, a securing-cylinder screwed on said extension and terminating in a smaller cylinder both parts being open from end to end, a regulating-cylinder provided with internal teeth 10 and composed of two cylinders of different sizes placed end to end located within said securing-cylinder, said regulating-cylinder being open from one end to the other, a handle secured to said regulating-cylinder, a bolt 15 screwed into the extension on the casing and engaging one side of said regulating-cylinder, and a valve-cylinder passing through the extension on the casing and having a closed upper end with a gear-wheel attached thereto.
17. In a rotary drill, the combination of a 20 casing provided with a perforated extension, a perforated valve-cylinder secured in said extension, said valve-cylinder being provided with a central bore closed at one end with a 25 gear-wheel fastened to said closed end and with inlet and outlet ports, a regulating-cylinder provided with internal gear-teeth meshing with the teeth on the gear-wheel of said 30 valve-cylinder, a handle attached to said regulating-cylinder, operating-cylinders provided with inlet and outlet ports adapted to communicate with the bore in said valve-cylinder, the parts being so arranged that when the teeth on said gear-wheel are centrally arranged in relation to the teeth on the regulating-cylinder, a movement of the handle in either direction will first decrease the flow of the motor fluid in said valve-cylinder, then 35 cut it off and then reverse the flow thereof in 40 said operating-cylinder.
18. In a rotary drill, the combination of a casing, a supporting-ring secured to said casing, said ring being eccentrically perforated, a valve-cylinder located in the perforation in 45 said ring, a plurality of cylinders revolubly supported on said valve-cylinder, crank-arms, a spider-ring revolubly supported on said supporting-ring, connections between said crank-arms and spider-ring, pistons in said cylinders, piston-rods pivotally connected to said 50 connections and to said pistons, and means for turning said valve-cylinder, to stop or reverse the drill.
19. In a rotary drill, the combination of a 55 casing, a supporting-ring eccentrically perforated secured to said casing, a valve-cylinder passing through the perforation in said supporting-ring, a spider-ring mounted on said supporting-ring, antifriction devices between 60 said spider-ring and said supporting-ring, a plurality of cylinders revolubly supported on said valve-cylinder, pistons in said cylinders, crank-arms, connections between said crank-arms and spider-ring, piston-rods pivotally 65 connected to said connections and said pistons, and means for turning said valve-cylinder, to stop or reverse the drill.
20. In a rotary drill, the combination of a casing, a supporting-ring eccentrically perforated secured to said casing, a valve-cylinder 70 closed at one end and open at the other passing through the perforation in said supporting-ring, a spider-ring revolubly mounted on said supporting-ring, antifriction devices between said spider-ring and said supporting-ring, a plurality of cylinders supported on said valve-cylinder, pistons in said cylinders, crank-arms, connections between said crank-arms and said spider-ring, piston-rods pivotally connected to said connections and to said 75 pistons, and a handle for supporting the drill and for rotating said valve-cylinder, whereby the motion of the pistons in said cylinders may be stopped, started or reversed at will.
21. In a rotary drill, the combination of a 80 casing provided with internal gear, a spider-frame provided with gearing meshing with said internal gear, a tool-holder secured to said spider-frame, crank-arms, gearing thereon, a spider-ring, connections between said 85 spider-ring and said crank-arms, a plurality of revolving cylinders, pistons in said cylinders, piston-rods pivotally connected to said connections and to said pistons, and means for regulating the flow of the motor fluid to 90 said cylinders.
22. In a rotary drill, a casing made in two parts secured together by bolts, one part of said casing being provided with an open-ended cylindrical extension and with openings for the escape of the motor fluid, the opposite part of said casing being provided with an opening for the admission of the motor fluid, said opening being provided with screw-threads and with a shoulder, and said upper 95 part being provided with a perforated screw-threaded extension.
23. In a rotary drill, the combination of a 100 casing provided with an inlet-opening, a supporting-ring secured to said casing, said supporting-ring being eccentrically perforated for the passage of the valve-cylinder and being provided with a passage at right angles to said eccentric perforation, a pipe connected with said passage, thimbles secured to one 105 end of said pipe, a revoluble valve-cylinder mounted in the eccentric perforation of said supporting-ring, and operating means for the tool consisting of pistons, cylinders and gearing supported on said supporting-ring.
24. In a rotary drill, the combination of a 110 casing provided with an internal gear, a spider-frame provided with a cylindrical extension, a tool-holder mounted in said extension, gearing including a central gear-wheel 115 and connecting gear-wheels between said central gear-wheel and the gearing on said casing, crank-arms attached to said central gear-wheel, extensions carried by said crank-arms, operating-cylinders, pistons in said cylinders, 120 and piston-rods pivoted to the extensions on the crank-arms and to said pistons.
25. In a rotary drill, the combination of a 125 casing consisting of two parts connected to-

gether, one part of the casing being provided with exit-openings, and the opposite part of the casing being provided with an inlet-opening having screw-threads and a shoulder, an 5 inlet-pipe screwed into said inlet-opening, a pipe in said casing for conducting the motor fluid, a thimble engaging the lower end of said pipe, a hollow nut screwed into said thimble and engaging the shoulder on the inlet- 10 opening of said casing, a perforated ring in which the other end of said pipe engages, a perforated valve-cylinder closed at one end mounted in said ring, and operating parts driven by the motor fluid passing through the 15 parts above mentioned.

26. In a rotary drill, the combination of a casing having an internal gear, a perforated supporting-ring secured to said casing, a perforated rotatable valve-cylinder located in 20 said perforated ring, means for rotating said valve-cylinder to stop, start and reverse the machine, cylinders operated on said valve-cylinder, pistons in said cylinders, a spider-frame, a tool-holder mounted therein, and 25 connections and gearing between said pistons and said spider-frame.

27. In a rotary drill, the combination of a valve-cylinder and a valve therein, said valve-cylinder being closed at one end and open at 30 the other, provided with inlet-ports and exhaust-ports at different levels, and said valve being composed of a rectangular portion having a concaved upper end and a circular portion fitting in the bore of said valve-cylinder, 35 said valve being secured in said valve-cylinder so that the circular portion is located between the inlet and outlet ports, operating cylinders revolvably mounted on said valve-cylinder, and connections whereby the movement of the pistons operates the tool. 40

28. In a rotary drill, the combination of a casing, a supporting-ring secured to said casing and provided with an eccentric perforation, a valve-cylinder passing through said 45 perforation, means for rotating said valve-cylinder, a valve located in said valve-cylinder, a support provided with cylinders made integral therewith mounted on said valve-cylinder, means for securing said support and 50 cylinders to said valve-cylinder, a spider-ring mounted on said supporting-ring, crank-arms, connections between said crank-arms and spider-ring, pistons in said cylinders, piston-rods pivotally connected to said connections and to said pistons, a spider-frame provided with a tool-holder, and gearing between 55 said spider-frame and said crank-arms.

29. In a rotary drill, the combination of a casing provided with an internal gear, a sup- 60 porting-ring secured to said casing and provided with an eccentric perforation, a valve-cylinder in said perforation, means for rotating said valve-cylinder, a valve in said valve-cylinder, a support having three cylinders 65 cast integral therewith, means for mounting said support upon said valve-cylinder, a spider-ring movably supported on said sup-

porting-ring, crank-arms, connections between said arms and spider-ring, pistons in said operating-cylinders, piston-rods pivotally connected to said connections in said pistons, a spider-frame, a tool-holder carried by said spider-frame, and gear-wheels mounted on said spider-frame engaging with each other, and with internal gear on the casing. 70

30. In a rotary drill, the combination of a casing made in two parts and provided with inlet and outlet openings, a supporting-ring secured to said casing, said ring having an eccentric perforation, a valve-cylinder passing through said perforation, means for rotating said valve-cylinder, a valve in said valve-cylinder, an integral structure composed of the central support and radial cylinders all made in one piece, means for supporting said 85 structure on said valve-cylinder, a spider-ring revolvably mounted on said supporting-ring, crank-arms, connections between said ring and arms, pistons in said operating-cylinders, piston-rods pivotally connected to said 90 connections and said pistons, a spider-frame provided with a tool-holder and gearing, whereby said crank-arms drive said spider-frame and tool-holder.

31. In a rotary drill, the combination of a 95 casing provided with internal gear and inlet and outlet openings, a supporting-ring provided with an eccentric perforation secured to said casing, a valve-cylinder passing through said perforation, a valve in said cylinder, a structure consisting of a central perforated support and three radial operating-cylinders revolvably mounted upon said valve-cylinder, means for securing said structure upon said valve-cylinder, a spider-ring revolvably mounted upon said supporting-ring, crank-arms, 100 connections between said spider-ring and crank-arms, pistons in said operating-cylinders, piston-rods pivotally connected to said 105 connections and to said pistons, a spider-frame provided with a tool-holder and planetary gearing mounted on said spider-frame and engaging with the internal gear on said casing. 110

32. In a rotary drill, the combination of a 115 casing made in two parts and provided with inlet and outlet openings, one part of said casing being provided with a cylindrical extension, a supporting-ring secured to said casing and provided with an eccentric perforation; a valve-cylinder closed at one end and mounted in said perforation, a valve in said 120 valve-cylinder, a structure consisting of a central support and radially-arranged operating-cylinders mounted on said valve-cylinder, means for securing said structure upon said valve-cylinder, a spider-ring rotatably mounted on said supporting-ring, crank-arms, 125 connections between said arms and ring, pistons in said operating-cylinders, piston-rods pivotally connected to said connections and to said pistons, a spider-frame provided with a cylindrical extension, a tool-holder mounted in said extension, and gearing whereby the 130

revolution of said crank-arms revolves said spider-frame.

33. In a rotary drill, the combination of a casing provided with inlet and outlet openings, one part of said casing being provided with a cylindrical extension, a spider-frame provided with a cylindrical extension which extension is located in the cylindrical extension of the casing, a tool-holder mounted in the cylindrical extension of the spider-frame, wear-plates secured to the cylindrical extensions of the spider-frame and casing, respectively, antifriction devices between said wear-plates, and means for rotating said spider-frame.

34. In a rotary drill, a spider-frame composed of a base and projecting arms perforated and provided with a cylindrical extension, the outer end of which is thickened and provided with an internal and with an external screw-thread.

35. In a rotary drill, a spider-frame consisting of a base and projecting arms, said base and arms being perforated and the perforated parts being thicker than the adjacent parts, said frame being also provided with a cylindrical extension, the outer end of which is thickened and finally reduced at the extreme end, said extension being provided with an internal and external screw-thread at the extreme end thereof.

36. In a rotary drill, the combination of a casing provided with inlet and outlet openings, a supporting-ring secured to said casing and provided with an eccentric perforation, a valve-cylinder mounted in said perforation, a valve mounted in said valve-cylinder, a structure comprising a central perforated support and radially-operating cylinders made integral therewith, said structure being mounted on said valve-cylinder, means for securing said structure upon said valve-cylinder, a spider-ring revolvably mounted on said supporting-ring, crank-arms, connections between said ring and arms, pistons in said operating-cylinders, piston-rods pivotally connected to said connections and to said pistons, a spider-frame provided with a tool-holder and operating-gearing consisting of an internal gear-ring located on said casing, a central gear-wheel mounted on said spider-frame, and gear-wheels meshing with said internal gear-ring and with said central gear-wheel.

37. In a rotary drill, the combination of a casing provided with inlet and outlet ports, a supporting-ring secured in said casing and having an eccentric perforation, a valve-cylinder mounted in said perforation, a valve in said valve-cylinder, a plurality of operating-cylinders connected to a central support mounted on said valve-cylinder, means for securing said operating-cylinders and support to said valve-cylinder, a spider-ring revolvably mounted on said supporting-ring, crank-arms, connections between said ring and arms, pistons in said cylinders, piston-rods pivotally connected to said connections and

to said pistons, a spider-frame, a tool-holder mounted therein and operating-gearing consisting of an internal gear-ring mounted on said casing, a gear-wheel centrally mounted on said spider-frame and connected to said crank-arms, and gear-wheels engaging with said internal gear-ring and with said central wheel.

38. In a rotary drill, the combination of a casing made in two parts united together with bolts and provided with inlet and outlet openings, a perforated ring secured to said casing, a valve-cylinder mounted in the perforation of said ring, a pipe in said casing connected with the inlet-opening and with one of the perforations in said supporting-ring, a valve in said valve-cylinder, operating-cylinders revolvably supported on said valve-cylinder, means for securing said operating-cylinders upon said valve-cylinder, a spider-ring revolvably supported on said supporting-ring, crank-arms, connections between said ring and arms, pistons in said operating-cylinders, piston-rods pivotally connected to said connections and said pistons, a spider-frame provided with a tool-holder, a central gear-wheel mounted in said spider-frame and connected to said crank-arms, connecting gear-wheels mounted on arms in said spider-frame and engaging the central gear-wheel and an internal gear-wheel mounted in the casing and engaging said connecting gear-wheels.

39. In a rotary drill, the combination of a casing made in two parts united together with bolts and provided with inlet and outlet openings, said inlet-opening being provided with a screw-thread and a shoulder, an eccentrically-perforated ring secured to said casing, a valve-cylinder mounted in the perforation of said ring, thimbles located in said inlet-opening, a pipe connecting said thimbles with one of the perforations in said supporting-ring, a valve in said valve-cylinder, operating-cylinders revolvably supported on said valve-cylinder, means for securing said operating-cylinders upon said valve-cylinder, a spider-ring revolvably mounted on said supporting-ring, crank-arms, connections between said spider-ring and arms, pistons in said operating-cylinders, piston-rods pivotally connected to said connections and said pistons, a spider-frame provided with a tool-holder, a central gear-wheel mounted in said spider-frame and connected to said crank-arms, connecting gear-wheels mounted on arms in said spider-frame and engaging the central gear-wheel, and an internal gear-wheel mounted in the casing and engaging said connecting gear-wheels.

40. In a rotary drill, the combination of a casing made in two parts united together with bolts and provided with inlet and outlet openings, a perforated ring secured to said casing, a valve-cylinder mounted in said ring, a pipe in said casing connected with the inlet-opening, and with one of the perforations in said supporting-ring, a valve in said valve-cylinder, operating-cylinders revolvably supported

on said valve-cylinder, a perforated nut and washer for securing said operating-cylinders upon said valve-cylinder, a spider-ring revolvably supported on said supporting-ring, 5 crank-arms, connections between said ring and arms, pistons in said operating-cylinders, piston-rods pivotally connected to said connections and said pistons, a spider-frame provided with a tool-holder, a central gear-wheel mounted in said spider-frame and connected to said crank-arms, connecting gear-wheels

mounted on arms in said spider-frame and engaging the central gear-wheel, and an internal gear-wheel mounted in the casing and engaging said connecting gear-wheels. 15

In testimony whereof we affix our signatures in presence of two witnesses.

CHARLES HERMAN HAESLER.
